KNITTING MACHINE

William D. Gorman, Philadelphia, Pa., and Charles Moses, New York, N. Y., assignors to H. Brinton Company, Philadelphia, Pa., a corporation of Pennsylvania

Application October 2, 1934, Serial No. 746,566

18 Claims. (CL 66—50)

Our said invention relates to knitting machines and particularly to knitting machines having independent needles of the type wherein needles are individually selected by means of a design wheel as for making patterns. It is an object of the invention to provide improved mechanism whereby the needles may be separated into sets positioned at different elevations, such as welt level, tuck level and knitting level or any combination of such levels.

A further object of the invention is to provide a design wheel of improved construction.

Referring to the drawing, which is made a part of this application and in which similar reference characters indicate similar parts:

Fig. 1 is an elevation of a part of a knitting machine provided with our improved devices;

Fig. 2, a section on line 2—2 of Fig. 1,

Fig. 3, a partial section of the design wheel, and

Fig. 4, a plan with parts broken away.

In the drawing, reference character 10 indicates a needle cylinder of conventional character, in the slots of which there are located needles 11 having outwardly projecting butts adapted to be engaged by cams such as stitch cams 12, filling cam 13 and needle raising cam 14. Conventional sinkers are indicated at 15, the sinkers being located in a bed 16 secured to the needle cylinder and being actuated by cams on the sinker ring 17.

Commonly, but not necessarily, the cams of a feed are held on a block constituting a section of the cam ring and here indicated at 18, such a section including in this case a stitch cam 12, a raising cam 14 and filling and other cams as convenience or necessity may indicate. The section in this case also includes a design wheel indicated generally at 19 in Fig. 2, said wheel being mounted for rotation on a post 20 secured to a bracket 21, said bracket having a foot 22 extending into the block 18.

The design wheel comprises a pair of plates 23 and 24, the lower plate having a central boss 25 for centering the upper plate, said boss also centering a holding plate 26. The plates 23 and 24 are each provided about their periphery with parallel teeth 27 of the usual type with slots between them and such slots extending obliquely from edge to edge of the plate. At a short distance inward from the edge of the plate an annular recess is provided at 28 and 29 in the respective plates and the intermediate plate 24 is also reduced in thickness at its under side, from a depending shoulder 30 to the central opening of the plate, while the holding plate 26 is similarly reduced in thickness inwardly from a shoulder 31. Inserts 32 are adapted to be positioned with their outer ends in the peripheral slots for the purpose of engaging needle butts to

raise the needles selectively, the distance to which the needles are raised depending upon whether a needle butt is engaged by an insert of the lower set or of the upper set, in the embodiment of the invention here illustrated.

The inserts are enlarged at their inner ends as shown at 33, so as to be securely held in place between the plates, which are reduced in thickness at appropriate points as hereinbefore described. The plates 23 and 24 are fastened together by means of screws 34 and the holding plate 25 is secured to plate 24 by screws 35.

In order that the plate 24 may be correctly positioned circumferentially with reference to the base plate, so as to insure the desired pattern relation between the two plates and so as to fix the slots of the two plates in alignment and in position for proper engagement with the needle butts the lower plate is provided with a pin 36 adapted to enter a hole 37 in the upper plate when the plates are superposed. A nut 38 holds the wheel on the post, the usual spacer 39 and other conventional parts serving to insure free rotation of the wheel.

Preferably a filling cam 13 is so positioned that the needles approach the design wheel at welt level and preferably also the cam 14 has an active face so located as to cause the needle butts to travel obliquely in a path approximately parallel to and nearly identical with the plane of the adjacent part of the upper face of the wheel, so that the needle butts pass smoothly off the cam and are raised by an insert of the lower series if the needle is to be elevated to tuck level as indicated at 40 or by an insert of the upper series if the needle is to be elevated to knitting level as indicated at 41. For the usual purposes of our invention the wheel will also have open slots not provided with inserts which open slots allow the needles to remain at an idle level as indicated at 42. This idle level, in the illustrated embodiment of the invention is higher than the welt level as indicated by the needle at 43. It is desirable to restore the idle needles to welt level and we therefore provide at 44 a depressing cam which engages the butts of idle needles and depresses them to welt level, as indicated by the needle at 45. It will be obvious that the depressing cam could be positioned so as to depress other needles than those at the level indicated in the drawing if desired and it will also be obvious that in this or in other ways the wheel of our invention may be used for separating the needles into two sets instead of three sets as here shown, the specific division depending on the particular results desired to be obtained.

Many other changes in our improved mechanism and its methods of use will be obvious to those skilled in the art and therefore we do not limit ourselves to what is shown in the drawing.

and described in the specification, but only as indicated in the appended claims.

It will be obvious also that our mechanism may be utilized for separating other devices such as jacks, or for separating needles by acting on their jacks and therefore such terms as "needle butts" are to be understood as being used for clearness in the claims and not for limitation except as required by the state of the art.

10 Having thus fully described our said invention, what we claim as new and desire to secure by Letters Patent is:

1. In a knitting machine, a stitch cam, an inclined design wheel for elevating needles selectively into position to be depressed by said stitch cam, means on said wheel for raising needles selectively to either of two elevations, and needle depressing means between said wheel and said cam.

20 2. In a knitting machine, an inclined design wheel having slots for idle needles and also having means for raising other needles selectively either to tuck level or to knitting level, and means to depress the idle needles after they pass the design wheel.

30 3. In a knitting machine, an inclined design wheel having slots for idle needles and also having means for raising other needles selectively either to tuck level or to knitting level, means to depress the idle needles after they pass the design wheel, and means for causing the needles to approach the wheel at welt level.

40 4. In a knitting machine, an inclined design wheel having slots for idle needles and also having means for raising other needles selectively either to tuck level or to knitting level, means to depress the idle needles after they pass the design wheel, means for causing the needles to approach the wheel at welt level, and means adjacent said wheel for causing the butts of the needles to travel in a line approximately parallel to the plane of the wheel.

50 5. In a knitting machine, an inclined design wheel having slots for idle needles and also having means for raising other needles selectively either to tuck level or to knitting level, a stitch cam and means between said wheel and the stitch cam for depressing the idle needles.

60 6. In a knitting machine, the combination of a section including a stitch cam, a design wheel having teeth for driving the wheel with slots between them for idle needles, needle-raising inserts for said wheel, and means on said wheel adapted to hold said inserts at different levels thereon between pairs of such teeth for raising selected needles to different heights.

70 7. In a knitting machine, the combination of a section including a stitch cam, a needle raising cam, a design wheel positioned to elevate selectively the butts of needles raised by said raising cam, said design wheel including open slots for idle needles and also including means to raise other needles selectively either to tuck level or to knitting level, and a cam to depress the idle needles to welt level.

8. In a knitting machine, the combination of a section including a stitch cam, a needle raising cam, a design wheel positioned to elevate selectively the butts of needles raised by said raising cam, said design wheel including open slots for idle needles and also including means to raise other needles selectively either to tuck level or to knitting level, a cam to depress the idle needles

to welt level, and a cam for causing the needles to approach the design wheel at welt level.

9. In a knitting machine, the combination of a section including a stitch cam, a needle raising cam, a design wheel having slots for idle needles and also having means to engage the butts of needles actuated by said raising cam and to elevate them selectively either to tuck level or to knitting level, and needle depressing means between said stitch cam and said wheel.

10 10. A design wheel of the type adapted to elevate needles selectively, said wheel having oblique peripheral slots, and means fixed in said slots for elevating needles selectively to different levels.

11. A design wheel of the type for elevating needles selectively by engagement with their butts, said wheel having open slots for idle needles and also having means in fixed position thereon for elevating other needles selectively to two different levels.

20 12. A design wheel comprising a pair of separable closely adjacent plates each having parallel oblique slots on its periphery, means for fastening said plates together, means for insuring alinement of the slots of the respective plates when assembled, and means extending outward from the periphery of each plate for selectively elevating to different heights the needles of a series.

30 13. A design wheel having oblique parallel teeth about its periphery for engagement with needle butts to drive the wheel and interchangeable means in said slots at different levels axially of the wheel for engaging needle butts to lift the corresponding needles to different heights.

35 14. A design wheel comprising a pair of separable closely adjacent plates each having parallel oblique slots on its periphery, means for fastening said plates together, means for insuring alinement of the slots of the respective plates when assembled, and inserts in said slots adapted to receive needle butts at one level and elevate them to two different levels.

40 15. A design wheel of the type for moving needles selectively lengthwise, said wheel having fixed means for directly moving needles or jacks selectively lengthwise from one position to either of two other positions.

45 16. A design wheel of the type for moving needles selectively lengthwise, said wheel having fixed means for moving needles selectively lengthwise from one position to either of two other positions, said design wheel also having means whereby selected needles may pass it without being moved.

50 17. For use in a knitting machine having a series of reciprocal elements with butts thereon, a design wheel adapted to be mounted in oblique position adjacent said series, and means in fixed position on said wheel for engaging said butts directly to move said elements to different levels.

55 18. A design wheel having parallel teeth arranged in a circumferential series about its periphery and providing slots between them, said wheel comprising a plurality of separable plates, removable inserts for said wheel in said slots, means on at least two of said plates for positioning inserts circumferentially thereof, and means for fastening said plates together so that said inserts are fixed in position in sets at different levels axially of the wheel, the height of said inserts being such as not to extend beyond said teeth.
